UNITED STATES PATENT OFFICE.

JAMES HIRST, OF MELROSE, MASSACHUSETTS.

DIESTOCK.

Application filed February 19, 1924. Serial No. 693,883.

To all whom it may concern:

Be it known that I, JAMES HIRST, a citizen of the United States, residing at Melrose, in the county of Middlesex and State 5 of Massachusetts, have invented new and useful Improvements in Diestocks, of which the following is a specification.

This invention relates to a tool including a stock or holder adapted to securely confine 10 and operate a pair of dies formed to cut male screw threads on a rod or bolt, and to permit the quick and convenient application and removal of the dies and the substitution of others therefor, as set forth in my Letters 15 Patent of the United States, No. 1,484,067, dated February 19, 1924.

The invention is embodied in certain improvements which I will now proceed to describe and claim, on the tool disclosed by 20 said application.

Of the accompanying drawings forming a part of this specification,

Figure 1 is a perspective view of the stock or holder, the dies, the die-securing tongues, 25 and the handles being removed.

Figure 2 is a longitudinal section of the entire tool, the handles being broken away.

Figure 3 is a side view, showing a work 30 guide engaged with the tool body.

Figure 4 is a section on line 4-4 of Figure 3.

The same reference characters indicate the same parts in all of the figures.

The body of the stock or holder is composed of duplicate side portions 12, 12, and end portions 13 and 14, said portions bounding an opening 15, adapted to receive a pair of dies 16. The dies have the usual acting portions 17, adapted to cut male screw 35 threads on a bolt or rod. The side portions 12 are provided with slots 19, communicating with the opening 15, said slots having extensions 19^a extending through the end portion 14, and along the periphery of a boss 20, formed on said end portion.

Connected by pivots 21 with the side portions 12, at one end of the holder, are two die-engaging bars or tongues 22, having their free ends reduced in width and provided with ears 23, adapted to enter the portions of the slot extensions 19^a that are formed in the boss 20. The dies 16 are provided, in opposite edges, with grooves 24 which receive the inner edges of the tongues 22, when the tongues are in their operative 50 positions.

The engagement of the tongues with the die grooves confines the dies against side-wise displacement, and permits endwise movement of the dies in the opening 15. 60

The tongues 22 are releasably confined by a tubular flange 26, formed on a handle 27. Said handle is provided with a screw-threaded shank 28, engaged with a tapped orifice in the boss 20. The ears 23 are flush with the boss 20, when the tongues are in their operative positions, and the arrangement is such that when the shank 28 is screwed inward, the flange 26 simultaneously overlaps and engages the ears 23, and 70 constitutes a keeper confining the tongues in engagement with the dies. When the shank 28 is screwed outward, the keeper simultaneously releases the ears 23, so that the tongues may be swung outward and thus 75 displaced, to release the dies and permit their sidewise removal.

When the tool is in use, one of the dies 16 is abutted against one end of the opening 15, as shown by Figure 2. The other die 80 is held by a screw-threaded shank 30, either against the abutted die as shown, or spaced therefrom by a rod or bolt to be threaded, interposed between the dies, when the diameter of the rod is such that the dies do not 85 meet. The shank 30 engages a tapped orifice in the end portion 13, and is provided with a handle 29. Said handle has a tubular flange 32, embracing and slidably on a tubular boss 31, formed on the end portion 13. 90

The die-confining shank 30 is fixed to the handle 29 and is longitudinally adjustable by rotation of said handle, to adjustably confine the die 16 with which it contacts. The handle 29 and the companion handle 95 27, aligned therewith, are grasped by the hands of the operator, as usual, when the stock is being turned or revolved to cut a screw thread.

The structure thus far described is that of 100 my Patent No. 1,484,067.

The die 16, shown at the left in Figure 2, and seated on one end of the opening 15, is non-adjustable, the other die is movable in the opening toward and from the non-adjustable die, and as before stated, may be held by the screw-threaded shank 30, either against the non-adjustable die, or spaced therefrom by a rod or bolt to be threaded, 105 interposed between the dies, when the diameter of the rod is such that the dies do not 110 meet.

When the dies do not meet and are spaced apart by the rod, the spacing of the dies determines the diameter of the thread cut on the rod. I provide indicating means for determining the spacing required to produce a thread of a given diameter, and locking means for securing the shank 30 in any adjusted position, and thereby maintaining any predetermined spacing of the dies. The locking means is embodied in a lock-nut 33, engaged with the thread of the shank 30, and adapted to be set up into binding engagement with a face 34 on the end portion 13, thus preventing rotative adjustment of the shank 30 and handle 29. The face 34 may be the bottom of a recess formed in the end portion 13, and communicating with the opening 15. The lock-nut 33 is preferably circular, and has a milled or knurled periphery, adapted to be engaged and turned by a thumb and finger.

The indicating means is embodied in a graduated scale 35, cooperating with an annular scale 36 (Figure 3) on the end of the tubular flange 32, to indicate the necessary adjustment of the shank for a given thread diameter.

It will now be seen that I am enabled to accurately adjust the adjustable die, to produce a thread of a predetermined diameter, by suitably rotating the shank 30, and to maintain the shank in any adjusted position, and thereby maintain any predetermined spacing of the die, this being accomplished before the stock is applied to a rod to be threaded. By forming the thread when the dies are spaced apart, I am enabled to subsequently decrease the size of the thread, if this is found desirable, by again decreasing the space between the dies.

The rod to be threaded is usually held in a vise during the threading operation, the end of the rod to be threaded being uppermost. The aggregate length of the stock including the handles, is such that unless great care is exercised by the operator, the stock is liable to be tipped or inclined more or less, relative to the axis of the rod, the latter being, as above stated, fixedly held as by a vise. To prevent this liability I provide a cross-bar 38, slidably engaged by ears 39, on its opposite ends, with the oppo-

site edge portions of the body 12. The cross-bar extends across the opening 15, at one side of the body, and is provided with an elongated opening 40, formed to closely embrace a substantial portion of a rod 41 at one side of the dies, and prevent the tipping of the stock on the rod. The opening 40 is preferably formed by a bushing 42, having an externally threaded portion, engaged with a tapped orifice in the cross-bar. The bushing may be used interchangeably with other bushings having openings 40 of different sizes. The cross-bar is formed to be slipped on to either end of the body, and to slide thereon to its operative position, the inner side of the cross-bar being provided with a recess 43, enabling the cross-bar to be moved across either of the enlarged or thickened ends 13 and 14 of the body.

The axis on which the stock is turned is a point equi-distant from the acting portions of the dies 16, and is therefore, variable and determined by the adjustment of the adjustable die, or the spacing between the two dies. The cross-bar, slidably, as stated, on the body 12, is adjustable to conform to any variations of the axis of the stock.

I claim:

A die stock comprising a body, two dies arranged within an opening in the body, means permitting relative adjustment of the dies to vary the width of the space between them, and a tubular guide for the article being threaded supported on the body and projecting laterally from one face thereof, the bore of said guide including a section, extending outward from the end adjacent the dies and having throughout its length a uniform diameter corresponding to that of the article to be threaded, providing means for engaging a considerable length of said article and preventing any tipping or lateral movement thereof relative to the dies, for insuring proper starting of the thread, the guide being movable longitudinally of the body out of alignment with the space separating the dies, whereby it may be positioned so as not to interfere with cutting a thread throughout the length of a bolt or rod.

In testimony whereof I have affixed my signature.

JAMES HIRST.
